OBSERVATION AND ANGLE-DETERMINING
INSTRUMENT

Frederick H. Hagner, San Antonio, Tex., assignor
to Archbold-Hagner Instrument Laboratory,
Inc., a corporation of Delaware

Application December 5, 1940, Serial No. 368,698

10 Claims. (Cl. 33—206)

1

This invention relates to an observation and angle-determining instrument, and has for one of its objects the production of a simple and efficient means for determining, by direct observation, the angular position of a ship, plane and the like, at a given time with respect to a horizontal or vertical plane.

A further object of this invention is the production of a simple and efficient means for recording the angular position of a plane, ship and the like, at a given time relative to a horizontal or vertical plane, whereby the readings while taking observations of celestial bodies and the like, by direct observation may be conveniently checked with the record of the angular position of the observation instrument at the time of observation to more accurately obtain a proper calculation as to an observer's position with respect to the body being observed.

A still further object of this invention is the production of a simple and efficient recording means for providing a permanent record of the angular position of the device with respect to the vertical and horizontal planes, at a given time, thereby recording the angle of tilt of the instrument in all directions, away from the true vertical, while making an observation.

Other objects and advantages of the present invention will appear throughout the following specification and claims.

In the drawings:

Figure 1 is a side elevational view of the observation and angle-determining instrument;

Figure 2 is a rear elevational view thereof;

Figure 3 is a vertical sectional view, certain parts being shown in elevation;

Figure 4 is a vertical section taken on line 4—4 of Figure 3;

Figure 5 is a vertical sectional view taken on line 5—5 of Figure 3;

Figure 6 is a fragmentary side elevational view of the micrometer release;

Figure 7 is a vertical sectional view taken on line 7—7 of Figure 1;

Figure 8 is an end elevational view looking at the outer end of the observation tube;

Figure 9 is a top plan view of the glass or transparent plate which supports the recording strip of paper and illustrating a fragment of the recording strip of paper;

Figure 10 is a front elevational view of the transparent plate or glass carried by the observation tube near the outer end thereof.

By referring to the drawings it will be seen that 10 designates handle which may be in the nature

2

of a hollow tube suspended in threaded engagement with a head 11. An observation tube 12 is carried by the upper end of the head 11 and extends at right angles to the handle 10, the handle normally extending substantially in a vertical position and the observation tube 12 normally extending in a horizontal position. A stop watch may be carried by the observation tube 11 to record the exact time at which the observation 10 is being made.

The observation tube 11 preferably comprises an elongated tubular member having an eye-piece 14 at its inner end, which eye-piece supports a plain glass panel 15. A light-varying segment 16 is pivotally secured, as at 17, within the eye cap 14, and is provided with a knurled finger-engaging portion 18 at its upper end to facilitate the swinging of the light-varying segment 16. The light-varying segment 16 preferably is provided with three light openings 19, 20 and 21, arranged on an arc with respect to the pivot 17 so as to be swung across the center of the glass panel 15. The light opening 19 may be a clear opening, the light opening 20 a shaded opening, and the opening 21 a shaded opening with a clear small center opening 22. In this way, the light-varying segment 16 may be swung to a position over the center of the panel 15 to correspond with the intensity of the light which 30 is being viewed through the observation tube 11.

The outer end of the observation tube 11 is provided with a glass panel 23 having a luminous spot 24 formed in the exact center thereof, this luminous spot being of transparent luminous material, so that at night when a star is sighted through the observation tube 11 the brilliancy of the star may be viewed through the transparent spot to enable an observer to place the spot in a dead-center with respect to the object being 40 viewed, such as a star of a smaller relative size. When viewing larger objects the luminous spot will facilitate the placing of the spot in the exact center of the object being viewed, for instance as when viewing the sun which is a 32-minutes 45 arc the luminous spot or dot has a dimension with respect to the celestial body of a 20-minutes arc. In this way an observer may determine whether or not the spot is toward the edge of the arc of the sun or is in the dead-center. The observer also in this way may utilize the optics of 50 the eye to replace the usual lenses which are employed in many instruments of this character.

A graduated quadrant 25 is hung from the observation tube in the manner shown and this 55 quadrant is provided with rack teeth 26 upon its

periphery which teeth are adapted to be engaged by a suitable micrometer screw 27, this screw being so adjusted as illustrated in dotted lines in Figure 6 to permit the release of the screw from the rack teeth 26 by compressing the trigger 28. Any well-known type of means may be utilized for this purpose to permit the micrometer screw 27 to be properly adjusted by rotating the knob 29 or to permit the hanger frame 30 to be freely swung when the trigger 28 is compressed to release the screw 27 from the rack teeth 26. The quadrant 25 as above stated, is hung from the observation tube and is also hung upon the shaft 31 which extends transversely through the head 11. This quadrant is fixed at its lower end 15 in any suitable manner to the handle 10 to hold the quadrant 25 in anchored relation with respect to the handle 10.

The hanger 30 is journaled for free swinging movement upon the shaft 31 and is held in slide- 20 able engagement with the quadrant 25, as shown in Figure 3, and may be connected thereto in any convenient or desired manner. The micrometer screw 27 is also anchored in engagement with the hanger 30 in the manner shown or in any other suitable manner so as to permit the screw 27 to contact with the rack teeth 26 or to be moved out of engagement with these rack teeth by compressing the trigger 28.

The shaft 31 carries a ball-bearing journal 32 adjacent the hanger 30 and a ball-dropping housing or casing 33 is journaled upon the ball-bearing journal 32, as indicated at 34, for constituting a bearing journal. A brake mechanism comprising the shaft 31 is employed, which shaft 31 is movable longitudinally by means of a cam trigger 35 which when swung to the position shown in Figure 3 will lock the brake shoe 36 against the outer end of the bearing section 32^a of the bearing journal 32 and hold the journal 40 portion 34 against rotating movement, and thereby lock the ball-carrying housing against swinging movement when desired.

The ball-dropping housing 33 is carried by the journal 34 as shown, and the trigger 35 may be swung to the position shown in dotted lines to release the brake shoe 36 and permit the housing 33 to freely swing in a pendulum-like manner together with the hanger 30.

The ball-dropping housing 33 is provided with a vertical bore 37 the upper end of which carries an Alnico magnet 38 which is in the nature of magnetized metal and is of any desired or usual shape, and is slidably mounted within the channel 39 carried by the cap 40 of the ball-dropping housing 33. This magnet 38 is connected to a bell crank lever 41, which bell crank lever 41 is actuated by a cam 42 the cam being carried by a shaft 43 and in turn being operated by a spring-pressed trigger 44 carried by the handle 10 as shown in Figure 5. Consequently, by compressing the trigger 44 the shaft 43 will be rotated in turn rotating the cam 42 swinging the bell crank lever 41 and lifting the magnet 38 bodily in a vertical direction in a manner for the purpose hereinafter described.

It will be noted that the casing or ball-dropping housing 33 has a pronounced longitudinal extent and that the retractile missile-supporting means or magnet 38 is longer than it is wide. 70 This magnet 38 is carried near one end of the casing or housing 33, as shown in Figure 3. A free-falling missile, such as one of the balls 48, is releasably held by the missile-supporting means or magnet 38. The missile-supporting means or

75 magnet 38 is mounted for bodily sliding longitudinal movement with respect to the casing or housing 33, in a direction away from the missile to release the missile.

A ball-guiding tube 45 is carried by the housing 33 and extends to a point adjacent the lower end of the channel 39. A rotating valve 46 is carried near one end of the tube 45 and communicates with a spring-pressed ball-carrying magazine 47 extending vertically of the housing 33 in a manner as shown in Figure 3. Balls 48 are carried within the magazine 47 and are carried to the valve 46. This valve 46 is rotated by means of a trigger 49, the valve 46 having an open side for receiving the balls 48. As the trigger 49 is depressed and the valve 46 rotates the open side of the valve 46 will be brought into registration with the end of the tube 45, and the ball will be fed down through the tube 45 to a position to contact with the lower end 50 of the depending tube 51. Before rotating the valve 46, however, a supporting element 52 which is journaled, as at 53, is swung from the position shown in full lines to the position shown in dotted lines in Figure 3 by depressing the trigger 54. The supporting element 52 when in the position shown in dotted lines will prevent the ball when contacting with the lower end 50 of the tube 51 from dropping momentarily until the ball is acted upon by the magnetic force of the magnet 38 and firmly held in position thereby. The trigger 54 is then released and the supporting element 52 drops to the position shown in full lines.

The magazine 47 may be of a conventional type but is preferably held in threaded engagement with the lower end 33^a of the housing 33 as shown. A channel 55 leads from the lower end of the bore 37 to a point near the lower end 33^a of the housing 33 to provide a pocket to permit accumulated balls within the bore 37 to pass to a position where the balls may be placed within the magazine 47. The magazine 47 may be withdrawn from the housing 33 to receive the balls within the channel 55 and may then be replaced to the position shown in Figure 3 for feeding the balls 48 to a point where they may be engaged individually at selective intervals by the magnetic force of the magnet 38.

A glass plate 56 is supported at the bottom of the bore 37 and is engaged by the upper end of a viewing tube 57, which tube extends up into the socket 58 of the housing 33. Paper reels 59 are rotatably mounted within the housing 33 upon opposite sides of the socket 58 so as to cause a strip of paper 60 to be reeled over the glass plate 56 at the upper end of the viewing tube 57. A suitable knurled knob 61 may be employed for operating the reel or reels 59. A hinged ribbon-carrying plate 62 is hingedly secured, as at 63, near one side of the bore 37 adjacent the plate 56 and is adapted to be swung down over the panel 56 and paper 60 from the position shown in full lines in Figure 3 in the direction of the arrow, and a suitable knob 64 is utilized for this purpose. This ribbon-carrying plate 62 carries a suitable strip of inked ribbon 62^a and when the ribbon 62^a is drawn in contact with the strip of paper 60, a ball dropping thereon will cause an impression to be made on the strip of paper. The housing 33 is provided with a window upon one side and a hinged window 66 on the opposite side. The hinged window 66 may be swung upwardly to permit an operator to place a suitable mark across the strip of paper 60 at the center of the viewing tube 57 to provide a gauge. The viewing

tube 57 is slidably mounted through a guide 67 anchored upon the lower end of the hanger 30 and this viewing tube 57 is vertically slidably mounted through the guide 67 so that the upper end of the tube 57 may be moved into and out of the socket 58 to hold the housing 33 in proper alignment with the viewing tube 57.

It should be understood that any suitable or desired type of means may be employed for raising the magnetized element or magnet 38 to withdraw the magnetic force away from the ball 50 and that any desired type of trigger arrangement may be utilized for this purpose without departing from the spirit of the invention.

When taking an observation, the operator will view an object through the observation tube 11 in a manner to cause the spot 24 to center upon the center of the object as accurately as possible and when the proper sight is taken the trigger 44 is compressed bodily moving the magnet 38 upwardly and urge the magnetic force away from the ball supported thereby, thereby releasing the ball and permitting the ball to drop as a free-falling mass upon the strip of ribbon 62a, which will cause a mark to be impressed upon the strip of paper 60 directly thereunder. By operating the triggers 54 and 49 the valve 46 will be opened and the supporting element 52 moved to a proper position to feed an additional ball 48 to a proper point, below the lower end of the tube 51 where the ball will be suspended by magnetic force by the magnet 38. The supporting element 52 is then dropped to the position shown in full lines in Figure 3. A second reading may then be taken and a second ball dropped to make a further impression upon the paper. In this way, a number of readings may be taken in a manner similar to that described in my previous Patent #2,219,990 issued October 29, 1940, and relating to an angle determining device. It should be understood that the magnet in the present instance constitutes a piece of highly magnetized material which will retain its magnetism over a maximum period of time, and that the ball is released by bodily moving the magnet to a position whereby the magnetic force will be weakened with respect to the ball and will permit the ball to drop by force of gravity to impress a mark upon the strip of paper 60 to obtain a reading of angle variance with respect to the vertical and horizontal planes. If the instrument is held in a true vertical, the ball which is dropped within the housing 33 will strike the center of the recording unit or recording means, but if the instrument is tilted at an angle to either side of the line of vision of the object observed, the impact of the ball when dropped upon the recording means during observation will record the angle of tilt. The degree of this angle of tilt must be computed and subtracted from the altitude angle which is measured on the instrument to determine the true angle of the object observed, measured from the true vertical or horizontal plane.

It should be understood that means may be provided if desired to automatically and periodically drop a series of balls one after another upon the recording means to give a reading of an average angle. This mechanism may embody a timing device for releasing these balls one at a time over a selected period of time and may be set in motion by pulling the trigger 44 or by any other means such as electrical release means.

It should be understood that in timing the observation, the viewing tube 57 is released or

withdrawn from the housing 33 permitting the housing 33 to freely swing in a pendulum-like manner through the force of gravity. The balls 48 by dropping through the housing 33 will record the angle of swing and the hanger 30 may then be swung to this angle and locked in position to obtain a proper reading upon the quadrant 25 and the relative markings upon the strip of paper 60 may be viewed through the medium of the viewing tube 57.

Attention is called to the fact that in Figure 1 the housing 33 is swung away from the viewing tube 57 for the purpose of showing the parts of the device and to emphasize the fact that this housing 33 may swing upon its journal independent of the hanger 30 and the housing 33 being also adapted to swing upon the shaft 31 when the housing 33 is secured in the position shown in Figure 3.

The observation tube carries a transparent plate or glass panel 23a as shown in Figure 1, and this transparent plate or glass panel 23a has crossed etched lines 23b formed thereon to facilitate the alignment of the junction of these crossed lines with the luminous spot carried by the transparent plate or glass panel 23.

The glass panel or plate 56 is preferably provided with a pair of spaced transverse etched lines 56a and a central crossed line 56b. The recording strip 60 is provided at spaced intervals with transverse short lines which are adapted to register with a similar line carried by the panel or plate 56. The dots in Figure 9 indicate the markings from the ball 48 upon the record strip 60. The operator may reach in through the window 66 and write on the strip 60 a suitable memorandum as to time, or make other notations if desired.

As shown in Figure 4, the housing 33 may be provided with a closure plate 33b adjacent the strip 60 to permit access to the strip 60 for replacement and access to the reels 59 by the removal of the plate 33b.

The micrometer screw and vernier 29 is provided with a rotatable band 29a which may be set independent of the vernier and locked in position by manipulating the member 29 so that the amount of turn of the vernier or micrometer screw may be observed after the setting for a comparison with the other readings of the instrument.

The instrument above described constitutes a recording and averaging sextant and provides a very light instrument for recording the altitude of celestial bodies by employing a ball-dropping device in the nature of a missile and a means for averaging the groups of dots on the recording strip or tape 60 and this instrument embodies an observation tube 11, the recording mechanism and housing 33, the altitude quadrant or arc 25 and the viewing or averaging unit 57.

The observation tube 11 is preferably constructed of a light material such as Dural having an overall length preferably eight inches, and a diameter of one and one-fourth inches. The eyecan or piece 14 consists of a small peep-hole described above. The transparent panel or glass 23a has etched or engraved crossed lines 23b and is placed in the tube 11 preferably five inches from the peep-hole. The glass or transparent panel 23 at the outer end of the tube 11 has the exact center thereof etched to provide a one-sixteenth of an inch circle which is filled with luminous paint one-thirty-second of an inch thick. The yellow glare from this luminous paint

permits a star or planet (such as the moon and the like) to be centered thereon. This then becomes the horizon or reference line. The eye-cap or piece 14 near the eye is provided with a means for varying the size of the opening to provide a sun-shade, and the like. It should be borne in mind that the present device provides a very efficient structure wherein the missile or ball 48 may be released by simply pulling the trigger 44 thereby avoiding dislocation or change of the position of the instrument to produce the desired record.

When using the device, the eye-piece 14 is placed near the eye of the observer and the brake 36 is released through the medium of the member 35 to permit the recording mechanism to swing in a pendulum-like manner to a substantially vertical position. A ball is fed to a proper position as described above to be suspended by the magnet 38 and when the horizon line or reference line registers with the body being observed, the trigger 44 is operated releasing the ball 48 which will drop upon the ribbon section 62^a and make a record upon the strip 60, to provide a permanent record of contact. This may be repeated for ten shots to obtain an average.

The averaging device is moved to a position directly over the viewing tube 57 to obtain a reading of the ten shots above mentioned, recorded on the strip of paper 60. This viewing tube 57 may be provided with a suitable magnifying lens. The micrometer screw 27 is moved until the etched line is in the center of the group of dots—then read the arc for the degrees and the micrometer screw drum for the minutes. This gives the altitude reading.

The instrument illustrated and described in this application is adapted to be used in substantially the same manner as a sextant, but the present instrument is constructed in such a manner as to measure an angle within an arc of 90°. This instrument may be, if so desired, attached to a sextant or octant in any conventional manner for the purpose of furnishing an artificial horizon, from which an angle of elevation may be measured.

Having described the invention what I claim as new is:

1. An angle-recording device of the class described comprising a casing, a magnetic element mounted for bodily movement and carried by the casing, a free-falling missile adapted to be suspended in one end of the casing by the magnetic element, a recording device carried near the opposite end of the casing, and means for bodily moving the magnetic element away from the missile for releasing the missile and causing the missile to freely fall by force of gravity and strike said recording means.

2. An angle-recording device of the class described comprising a casing, a magnetic element mounted for bodily movement and carried by the casing, a free-falling missile adapted to be suspended in one end of the casing by the magnetic element, a recording device carried near the opposite end of the casing, a trigger mechanism for bodily moving the magnetic element away from the missile for releasing the missile and causing the missile to fall freely by force of gravity and strike said recording means.

3. An angle-recording device of the class described comprising a casing, a magnetic element mounted for bodily movement and carried by the casing, a free-falling missile adapted to be suspended in one end of the casing by the magnetic element, a recording device carried near the op-

posite end of the casing, means for bodily moving the magnetic element away from the missile for releasing the missile and causing the missile to freely fall by force of gravity and strike said recording means, and means for feeding a missile to a point within the magnetic field of the magnetic element to cause the missile to be magnetically suspended within the magnetic field.

4. An angle-recording device of the class described comprising a casing, a magnetic element mounted for bodily movement and carried by the casing, a free-falling missile adapted to be suspended in one end of the casing by the magnetic element, a recording device carried near the opposite end of the casing, means for bodily moving the magnetic element away from the missile for releasing the missile and causing the missile to freely fall by force of gravity and strike said recording means, means for feeding a missile to a point within the magnetic field of the magnetic element to cause the missile to be magnetically suspended within the magnetic field, a missile reservoir, and valve means for releasing the missiles one-by-one to be fed to the magnetic element.

5. An angle-recording device of the class described comprising a casing, a magnetic element mounted for bodily movement and carried by the casing, a free-falling missile adapted to be suspended in one end of the casing by the magnetic element, a recording device carried near the opposite end of the casing, means for bodily moving the magnetic element away from the missile for releasing the missile and causing the missile to freely fall by force of gravity and strike said recording means, means for feeding a missile to a point within the magnetic field of the magnetic element to cause the missile to be magnetically suspended within the magnetic field, a missile reservoir, valve means for releasing the missiles one-by-one to be fed to the magnetic element, and a spring-pressed magazine fitting in the reservoir.

6. An angle-recording device of the class described comprising a casing, a magnetic element mounted for bodily movement and carried by the casing, a free-falling missile adapted to be suspended in one end of the casing by the magnetic element, a recording device carried near the opposite end of the casing, means for bodily moving the magnetic element away from the missile for releasing the missile and causing the missile to freely fall by force of gravity and strike said recording means, means for feeding a missile to a point within the magnetic field of the magnetic element to cause the missile to be magnetically suspended within the magnetic field, a missile reservoir, valve means for releasing the missiles one-by-one to be fed to the magnetic element, and a trigger for operating the valve means.

7. An angle-recording device of the class described comprising a casing, a magnetic element mounted for bodily movement and carried by the casing, a free-falling missile adapted to be suspended in one end of the casing by the magnetic element, a recording device carried near the opposite end of the casing, means for bodily moving the magnetic element away from the missile for releasing the missile and causing the missile to freely fall by force of gravity and strike said recording means, means for feeding a missile to a point within the magnetic field of the magnetic element to cause the missile to be magnetically suspended within the magnetic field, a missile reservoir, valve means for releasing the missiles one-by-one to be fed to the magnetic element, and movable means movable to a position under the

magnetic element for supporting a missile while it is being moved to a position within the magnetic field of the magnetic element.

8. An angle-recording device of the class described comprising a casing, a magnetic element mounted for bodily movement and carried by the casing, a free-falling missile adapted to be suspended in one end of the casing by the magnetic element, a recording device carried near the opposite end of the casing, means for bodily moving the magnetic element away from the missile for releasing the missile and causing the missile to freely fall by force of gravity and strike said recording means, means for feeding a missile to a point within the magnetic field of the magnetic element to cause the missile to be magnetically suspended within the magnetic field, a missile reservoir, valve means for releasing the missiles one-by-one to be fed to the magnetic element, and means forming a communication between the reservoir and the casing for directing the missiles from the interior of the casing to the reservoir.

9. An angle-recording device of the class described comprising a casing having a pronounced longitudinal extent, a retractible missile-supporting means longer than it is wide, said retractible missile-supporting means carried near one end of said casing, a free-falling missile releasably

held by said missile-supporting means, said missile-supporting means mounted for bodily sliding longitudinal movement with respect to said casing in a direction away from the missile to release the missile, a recording means carried near the opposite end of said casing, said missile being adapted to impact with said recording means to indicate the angle of incline and the angle of side-wise tilt of the casing during impact, means for releasing the missile from the supporting means, means for feeding a missile to the supporting means, a missile reservoir, and means for releasing the missiles from the reservoir one by one to be fed to the supporting means.

10. An angle-recording device of the class described comprising a casing, a recording means carried at one end of the casing, a reciprocating retractible missile-suspending element carried at the opposite end of the casing, a free-falling missile adapted to be suspended by said suspending element and also adapted to freely fall by force of gravity and strike said recording means when the missile is released, and means for bodily moving said suspending element away from said missile and in a direction opposite to the direction of fall of the missile for releasing said missile.

FREDERICK H. HAGNER.
